CASING FOR A WATER TESTER

Gomer S. Frank, 16311 Bircher St., Granada Hills, Calif.

Filed May 2, 1962, Ser. No. 69,946

Term of patent 14 years

(Cl. D16—2)

FIGURE 1 is a front perspective view of a casing for a water tester, showing my new design;

FIGURE 2 is a rear perspective view thereof;

FIGURE 3 is a front perspective view of a modified form of a casing for a water tester, shown in FIGURE 1; and

FIGURE 4 is a rear perspective view thereof.

I claim:

The ornamental design for a casing for a water tester, as shown and described.
